H. KOHNLE.

CIRCULATION SYSTEM FOR AUTOMOBILES.

APPLICATION FILED MAY 17, 1912.

1,158,691.

Patented Nov. 2, 1915.

UNITED STATES PATENT OFFICE.

HENRY KOHNLE, OF SPRINGFIELD, OHIO.

CIRCULATION SYSTEM FOR AUTOMOBILES.

1,158,691.

Specification of Letters Patent.

Patented Nov. 2, 1915.

Application filed May 17, 1912. Serial No. 697,896.

To all whom it may concern:

Be it known that I, HENRY KOHNLE, a citizen of the United States, residing at Springfield, in the county of Clark and State of Ohio, have invented certain new and useful Improvements in Circulation Systems for Automobiles, of which the following is a specification, reference being had therein to the accompanying drawing.

10 This invention relates to automobiles and more particularly to the water circulation system employed to cool the engine of an automobile.

15 The object of the invention is twofold; first, to provide means to prevent the cooling fluid from freezing in the engine or radiator; and second, to provide means for warming the passenger compartments of the automobile.

20 To this end it is also an object of the invention to provide means to drain the fluid from the water jackets, radiator and connecting pipes into a receptacle which is so insulated that the fluid in the same will not freeze; and further, to connect the system with suitable heating devices, such as heaters or foot warmers arranged in the passenger compartments; to provide means for controlling the passage of the water from 25 the jackets to the receptacle, whereby it may be caused to pass either directly from the radiator to the receptacle or through the radiator and through the heaters, then into the receptacle, or from the water jackets to 30 the heaters without passing through the radiators; and also to provide means for regulating the cooling action of the radiator on the water.

35 In the accompanying drawings, Figure 1 is a sectional view of a portion of an automobile showing my invention applied thereto; Fig. 2 is a sectional detail view of the controlling valve; and Fig. 3 is a detail of one of the foot warmers.

40 In these drawings I have illustrated one embodiment of the invention and have shown the same as applied to an automobile of ordinary construction having at its forward end an engine 1 provided with the usual water jacket which has conduits 2 and 3 leading to and from the same. Suitable means are provided for maintaining the circulation of water through the conduits and the water jacket. In order that this water 45 may not freeze in the water jacket or in the radiator 4, which is here shown as arranged

in front of the engine and connected to the outlet pipe 3 by means of a short pipe 5, it is desirable that some means should be provided for draining the water from the entire circulation system when the engine is to stand idle for any length of time during cold weather. To accomplish this I prefer to utilize a suitable water receptacle, such as a tank 6, which is supported adjacent to the circulation system and is here shown as supported beneath the frame of the automobile. This tank is completely surrounded with insulating material, such as wool fiber and asbestos, as indicated at 7, and is so protected that its contents will not freeze even in the most severe weather. Mounted within the tank and connected with the circulation system is the usual pump 8 by means of which the water is forced through the conduits, water jacket and radiator. Preferably, the tank is provided with a depressed portion forming a well within which the pump is mounted. By this means a sufficient depth of water is provided to enable the pump to operate until the tank is practically empty. In the form of the tank here shown the well is formed by a section 9 separate from and detachably secured to the main tank 6 by means of bolts 10. This well 70 section is protected in the same manner as is the tank proper and in fact forms a part of that tank and is in open communication therewith.

75 In the normal operation of the system the water which is discharged from the water jackets through the pipes 3 and 5 into the radiator 4 returns to the tank through a pipe 11 which is connected by means of a valve 12 with a short pipe 13 arranged to discharge into the tank. The valve 12, which is preferably a four-way valve, is also connected with a pipe 14 leading rearwardly along the passenger compartments and connected with heaters, such as foot 80 warmers 15, mounted in the passenger compartments. Each heater comprises merely a shallow casing, one wall of which forms a foot plate. This casing is provided with an outlet 16 which leads to the tank and is 85 smaller than the inlet. Consequently, the casing will be kept full of water and the foot plate will be heated. Any number of these heaters may be provided and they may be arranged in any desired positions. The outlet pipe 3 is also connected with the valve 12 and the tank by means of a pipe 17 con-

neeted at that end thereof opposite the pipe 5 which connects the outlet pipe to the radiator. Valves 18 and 19 are interposed between the pipes 5 and 17, respectively, and 5 the outlet pipe 3 and are so connected that when one of these valves is in its open position the other will be closed. This connection is preferably formed by a rod 20 which extends beyond the dash-board and has a 10 handle 21 which may be grasped by the operator to manipulate the valves. The four-way valve 12 is also provided with means for operating the same from the body of the car and, as here shown, a hand-wheel 22 is 15 mounted on the dash-board and connected by a shaft 23 and universal joint 24 with the valve. Any suitable means may be provided for indicating on the dash the position of the valve.

20 It will be apparent that with the valve 18 open and the valve 19 closed the water which passes through the outlet pipe 3 will pass through the radiator, thence through the pipe 11 and valve 12. If this valve is set to 25 connect the pipe 11 with the short pipe 13 the water will be discharged into the tank and then again pumped through the system to maintain the usual circulation. If the valve 12 is set to connect the pipe 11 with 30 the pipe 14 then the water from the jacket will pass through the heaters before it reaches the receptacle. If the circulation of the water through the heaters to the tank will cool the same sufficiently it may be de- 35 sirable to cut out the radiator and deliver the water directly to the heaters from the water jackets. This can be done by opening the valve 19, closing the valve 18 and setting the valve 12 to connect the pipe 40 17 with the pipe 14. If it is found that the heaters are not sufficiently heated with the water passing through the radiators and heated too much if the radiator is cut out altogether the temperature may be regu- 45 lated by providing means, such as a curtain 25, to cut off partly or entirely the passage of the air through the radiator and thus regulate the extent to which the water will be cooled while in the radiator. At the end 50 of a run when the engine is to stand idle for any material length of time in cold weather the valve 12 is set to connect the pipe 13 with the pipe 11. Consequently, the water 55 in the radiator and pipe 11 will drain into the tank and the water in the jackets and outlet pipe 3 will drain through the pump into the tank. The tank being effectually insulated there will be no freezing of the water in the tank and there will be no water 60 in the water jacket or any part of the circulating system to freeze.

While I have shown and described one embodiment of the invention it will be understood that the same has been chosen for 65 the purpose of illustration only and that I

do not desire to be limited to the details of construction shown and described, for obvious modifications will occur to a person skilled in the art.

Having thus fully described my invention what I claim as new and desire to secure by Letters Patent, is:—

1. An anti-freezing circulation system comprising an engine having a water jacket, a radiator, a conduit connecting said water jacket with said radiator, and a water receptacle supported adjacent to said engine and said radiator, conduits connecting said receptacle with said water jacket and said radiator, and a pump mounted in said receptacle to force water from said receptacle through said water jacket and said radiator, the several parts of said circulation system being so arranged relatively one to the other and to said receptacle that the water 85 in said system will automatically drain into said receptacle when the operation of said pump is interrupted.

2. The combination, with an engine having a water jacket, of a cold-resisting water 90 receptacle mounted below the level of said water jacket, conduits connecting said receptacle with said water jacket and arranged to drain into said receptacle, and a pump mounted in said receptacle to force 95 the water from said receptacle through said conduits and into said water jacket.

3. An anti-freezing circulation system comprising an engine having a water jacket, a water receptacle, a radiator, a connection 100 between said radiator and said receptacle, a pump mounted in said receptacle, a connection between said pump and said water jacket, and means to connect said water jacket either with said radiator or directly 105 with said receptacle, said pump, water jacket, conduits and receptacle being so arranged relatively to each other and to said receptacle that the water will automatically drain into said receptacle when said pump 110 ceases to operate.

4. The combination, with an engine having a water jacket, and an insulated water receptacle, of a pump mounted in said water 115 receptacle and connected with said water jacket, a radiator, a connection between said radiator and said water jacket, a connection between said radiator and said insulated receptacle, and means for controlling the flow of water through the last-mentioned connection.

5. The combination, with an engine having a water jacket, and an insulated water receptacle, of a pump communicating with the interior of said water receptacle and 125 connected with said water jacket, a radiator, a pipe extending from said radiator, a heater connected with said pipe and having a discharge pipe leading to said receptacle, a discharge pipe connected to the first-mentioned 130

pipe and communicating with said receptacle, and a valve to control the communication between said radiator and said heater and between the first-mentioned pipe and 5 the second-mentioned discharge pipe.

6. The combination, with an engine having a water jacket, and an insulated water receptacle, of a pump, a pipe leading from said pump to said water jacket, an outlet 10 pipe connected with said water jacket, a pipe leading from said water jacket to a point near said water receptacle, a valve connected with said pipe, another pipe leading from said valve to said water receptacle,

a radiator, a connection between said outlet 15 pipe and said radiator, and a pipe leading from said radiator to said valve, a heater, the last-mentioned pipe leading from said valve to said heater, said valve being capable of adjustment to connect said radiator 20 either with said heater or said receptacle or to connect said outlet pipe with said heater.

In testimony whereof, I affix my signature in presence of two witnesses.

HENRY KOHNLE.
